Term of patent 14 years

(Cl. D22—3)

FIG.1

FIG.6

FIG.5

A left side elevational view thereof would be substantially similar to the right side elevational view thereof of FIGURE 2.

I claim:

The ornamental design for a replaceable blade for a pinking machine, substantially as shown and described.
